CLAIM

The ornamental design for a fan blade, as shown and
described herein.

DESCRIPTION

FIG. 1 is a perspective view of a fan blade showing our new
design;

FIG. 2 is a top view thereof;

FIG. 3 is a bottom view thereof;

FIG. 4 is a front end view thereof;

FIG. 5 is a rear end view thereof;

FIG. 6 is a left side view thereof; and,

FIG. 7 is a right side view thereof.

The broken line showing of the fan blade in use is included
for the purpose of illustrating environmental structure and
forms no part of the claimed design.
